United States Patent Office

Des. 193,993
Patented Nov. 6, 1962

193,993

DISK-TYPE DATA STORAGE DEVICE

Dagmar L. Arnold, Palo Alto, Calif., assignor to International Business Machines Corporation, New York, N.Y., a corporation of New York

Filed June 8, 1962, Ser. No. 70,475

Term of patent 14 years

(Cl. D26—5)

FIG. 1

FIG. 2

FIG. 3

FIG. 1 is a front perspective view of a disk-type data storage device according to the present invention;

FIG. 2 is a rear perspective view of the device of FIG. 1; and

FIG. 3 is a plan view of the device of FIG. 1.
I claim:

The ornamental design for a disk-type data storage device, as shown.
